UNITED STATES PATENT OFFICE.

ELIZABETH M. POLLOCK AND MILTON POLLOCK, OF FLINT, MICHIGAN.

LINGERIE-STRAP HOLDER.

Application filed December 1, 1926. Serial No. 151,974.

This invention relates to lingerie strap holders and more particularly to a device for securing the shoulder straps of lingerie to the overlying portion of the dress which is of such construction that it will not produce a bulge or hump on the apparel and thus cause an unsightly appearance and will, at the same time, firmly secure the shoulder strap against dislodgment.

10 A further and more specific object of the invention is to provide a device of this character including a clasp for receiving and holding the shoulder straps and a pin pivotally connected with this strap adapted to pin into the shoulder seam of the dress and thus hold the clasp and accordingly the straps against movement, this pin being directed transversely of the clasp so that it is much more readily engaged with or 20 disengaged from the dress and is properly positioned for engagement in this seam, which provides the only possible anchorage point for the clasp.

These and other objects we attain by the construction shown in the accompanying drawing, wherein for the purpose of illustration is shown a preferred embodiment of our invention and wherein:—

Figure 1 is a plan view of the shoulder portion of a garment indicating a strap holder constructed in accordance with our invention in position therebeneath;

Figure 2 is a section on the line 2—2 of Figure 1;

Figure 3 is a section on the line 3—3 of Figure 1;

Figure 4 is a plan of the strip from which the clasp is formed;

Figure 5 is a top plan view of the complete strap holder.

Referring now more particularly to the drawing, the numeral 10 indicates a lingerie clasp which may be of any suitable character, but which is preferably formed from a folded metallic strip 11, one end of which is provided with a pressed recess 12 and the opposite end of which is provided with a small pressed head 13 producing a button which will engage in the recess 12 and be held in engagement therewith by the natural resiliency of the material to prevent disengagement of the ends of the clasp.

The material of the strip is longitudinally slit at transversely aligning points 14 adjacent opposite side edges thereof and the metal of the strip deformed at opposite sides of these slits, so that a guiding eye is produced through which may be directed one arm 15 of a safety pin, generally designated at 16. This arm is preferably the head bearing arm of the safety pin and is extended through the eye before the head 17 is applied to the pin, so that the safety pin cannot escape from the eye. By this arrangement, the pin 16 is extended transversely of the clasp 10 and pivotally connected therewith, so that it may swing down and lie flatly against the upper face of the band. It is also positioned, so that it may be directed transversely through the seam S formed in the shoulder portion of a garment G with much greater facility than it could were it directed longitudinally of the clasp. Furthermore, the clasp is so positioned, with respect to the pin by this construction, that there is no interference with the fingers by the clasp when the pin is being fastened.

Since the construction hereinbefore set forth is capable of a certain range of change and modification without materially departing from the spirit of the invention, we do not limit ourselves to such specific structure except as hereinafter claimed.

We claim:—

1. In combination with a metallic strip formed to provide a clasp for receiving and holding the shoulder straps of undergarments, the material of the strip being longitudinally slit at transversely aligned points lying intermediate the ends of the strip, the metal of the strip at opposite sides of said slits being oppositely deformed to thereby provide an eye and a safety pin having an arm thereof directed through said eye whereby the pin is pivotally connected with and extends transversely of the clasp.

2. In combination with a metallic strip formed to provide a clasp for receiving and holding the shoulder straps of undergarments, the material of the strip being longitudinally slit at transversely aligned points lying intermediate the ends of the

strip, the metal of the strip at opposite sides of said slits being oppositely deformed to thereby provide an eye and a safety pin having an arm thereof directed through said eye whereby the pin is pivotally connected with and extends transversely of the clasp, the arm of said pin directed through said

eye bearing the head of the safety pin whereby the safety pin is rendered unremovable from the eye. 10

In testimony whereof we hereunto affix our signatures.

ELIZABETH M. POLLOCK.
MILTON POLLOCK.
